UNITED STATES PATENT OFFICE.

RALPH W. WILSON, OF NEW YORK, N. Y., ASSIGNOR TO THEODORE W. FOSTER & BRO. COMPANY, OF PROVIDENCE, RHODE ISLAND.

ROUGE HOLDER.

Application filed February 14, 1925. Serial No. 9,122.

To all whom it may concern:

Be it known that I, RALPH W. WILSON, a citizen of the United States, residing at New York, in the county of New York and State of New York, have invented new and useful Improvements in Rouge Holders, of which the following is a specification.

This invention relates to certain new and useful improvements in rouge holders, and the primary object thereof is to provide a rouge holder of simple and novel construction provided with a mirror and a rouge container which latter may be easily and quickly moved to open position and held in the plane of the mirror during use of the latter thereby to enable the rouge to be applied without disturbing the position of either the mirror or the rouge container.

A further object of the invention is to provide a rouge container and refillers therefor, which latter may be easily and quickly applied.

A still further object of the invention is to provide novel means for movably mounting the rouge container and for latching same relative to the holder.

In the drawings:—

Figure 1 is a top plan view with the parts in open position;

Figure 2 is a section on line 2—2 of Fig. 1 and

Figure 3 is an end elevation, with the parts in closed position.

In proceeding in accordance with the present invention the holder consists of a body which is composed of a top plate 1 provided with a mirror 2 on its outer face, and a bottom plate 3 the top and bottom plates being connected by end posts or studs 4 and 5. The top and bottom plates are depicted as being of elliptical or ovaloid shape, although it will be understood that other shapes, as desired, may be used equally as well.

The rouge container, is of approximately the shape as that of the body and has a bottom 6 formed with an opening 7 and a rim 8. The post 4 passes through the bottom, 3, of the container by means of which the container is pivotally connected at one end to the body so as to swing in a plane parallel to the fixed mirror and beneath the latter, the top 1 and the mirror affording a cover for the rouge container. The opposite end of the container has a finger piece or grip 10 and a struck-out latch 11 which latter

is adapted to snap into and out of engagement with the post 5.

The refillers consist of a pan 12 of substantially the shape as that of the containers and conformably fit therein, so that the bottoms thereof are exposed through the opening 7, permitting disengagement of the pan by engagement of the fingers with the bottom thereof to force same out of the container.

When the parts are in the position of Fig. 1 it will be seen that the rouge is held in the plane of the mirror and that the convergent sides of the adjacent ends of the body and container afford convenient concave-like finger grips A and B enabling the article to be easily and firmly held and with the rouge accessible for use without disturbing the position of the mirror or of the container. By gripping the two parts at the points A and B the device is not only conveniently held but at the same time such parts are held against relative swinging movement. The post 5 serves not only to connect the plates of the body but also as a keeper for the catch, while the post 4 serves not only to connect the plates, but also to afford a pivotal mounting for the rouge container.

Having thus described my invention, what I claim as new and desire to secure by Letters Patent is:—

1. In a rouge holder, a body consisting of spaced plates, a rouge container having a bottom with an opening therein and a rim receivable between the plates, a stud connecting the plates at one end thereof, a stud engaged with the container bottom and connected to the plates at their opposite ends to hold the plates spaced and to provide a pivotal mounting for one end of the container, a latch on the opposite end of the container engageable with the first named stud, and a cup removably and frictionally held in the container.

2. A rouge holder embodying a hollow body, a mirror carried by the outer face of the body, a rouge container receivable in the body and having an open top faced in the same direction as that of the mirror, and means to pivotally mount the container for movement into and out of the body to lie in substantially the plane thereof to render the rouge accessible while the mirror remains in a predetermined position.

3. In a rouge holder, a hollow body, a mirror on the outer face of the body, the body having an end provided with convergent sides, and a rouge container having an open top faced in the same direction as that of the mirror pivoted to the body at said end thereof to move in substantially the plane thereof and having sides converging toward said end of the body to cooperate with said convergent sides of the body to form concave-like finger grips in conjunction therewith.

4. In a rouge holder, a body having spaced plates, a mirror on the outer face of one plate, and a rouge container pivoted to the plates to swing into and out of the space therebetween, the container having an open top faced in the direction in which the mir-

ror faces and disposed in a plane substantially parallel to the plane in which the mirror lies.

5. In a rouge holder, a substantially elliptical body, an outwardly faced mirror fixed on the top of the body, a rouge container, and means to pivotally connect the body and container together at one end to permit relative swinging movement thereof in substantially the same plane whereby when in open position to lie in end to end relation thereby to afford substantially concave and opposite finger grips between the adjacent ends of the body and container.

In testimony whereof I have signed my name to this specification.

RALPH W. WILSON.
